UNITED STATES PATENT OFFICE.

GENEVIEVE EMERSON, OF PITTSBURG, PENNSYLVANIA.

DESIGN FOR A GLOVE-CLEANING FORM.

SPECIFICATION forming part of Design No. 33,839, dated January 1, 1901.

Application filed November 24, 1900. Serial No. 37,690. Term of patent 14 years.

To all whom it may concern:

Be it known that I, GENEVIEVE EMERSON, a citizen of the United States, residing at Pittsburgh, in the county of Allegheny, State of Pennsylvania, have invented and produced a new and original Design for a Glove-Cleaning Form, of which the following is a specification, reference being had to the accompanying drawing, forming part thereof.

The drawing shows a perspective view of my invention.

The leading features of my design consist of the base or support and the arms and hands mounted thereon.

Referring to the drawing, the base or support A, of rectangular shape, is provided with a pocket or receptacle B, which pocket or receptacle is particularly adapted for holding a liquid substance employed in cleaning gloves. Extending upwardly from the base A, substantially at right angles thereto and

on each side of the pocket B, are arms C, each arm terminating in a hand D. It will be noted that one of the hands is designed to receive a glove for the right hand and the other for a left-hand glove. The fingers E and the thumbs F of each hand are separated or spaced in such a manner as to permit a small brush or other article to be passed between them while cleaning the fingers of the glove.

Having thus described my invention, what I claim as new, and desire to secure by Letters Patent, is—

The design for a glove-cleaning form, substantially as shown and described.

In testimony whereof I affix my signature in presence of two witnesses.

GENEVIEVE EMERSON.
